DOCUMENT SORTER CABINET

Charles P. Breed and Edward H. McCauley, Dallas, Tex.,
assignors to Sperry Rand Corporation, New York, N.Y., a corporation of Delaware

Filed Mar. 14, 1963, Ser. No. 73,965

Term of patent 14 years

(Cl. D26—5)

Fig. 1.

The portions of the design in FIGURE 2 showing diagonal shading, are so shaded to indicate the transparent surface.

We claim:

The ornamental design for a document sorter cabinet, as shown and described.
